(57) **CLAIM**

The ornamental design for an apparatus for pet hair removal, as shown and described.

DESCRIPTION

FIG. 1 is a front, top, left side isometric perspective view of an apparatus for pet hair removal in accordance with our design;

FIG. 2 is a front, top, right side isometric perspective thereof;

FIG. 3 is a front elevation view thereof, the rear elevation view being identical;

FIG. 4 is a left side elevation view thereof, the right side elevation view being identical;

FIG. 5 is a top plan view thereof; and,

FIG. 6 is a bottom plan view thereof.

The broken lines illustrate portions of the apparatus for pet hair removal which form no part of the claimed design.

The line shading and stippling shown in the drawings represent a contrast in materials.
